United States Patent Office

Des. 183,623
Patented Sept. 30, 1958

183,623

FOOD DRAINER

William Marcus, Cleveland, Ohio

Application May 13, 1958, Serial No. 50,867

Term of patent 7 years

(Cl. D44—29)

Fig. 1 is a front perspective view of a food drainer, showing my new design;

Fig. 2 is a top perspective view of the handle face thereof;

Fig. 3 is a perspective view of the opposite face thereof; and

Fig. 4 is an end elevational view of the same.

I claim:

The ornamental design for a food drainer, as shown.
